UNITED STATES PATENT OFFICE.

JENS JORGENSEN OVE FISCHER, OF RACINE, WISCONSIN, ASSIGNOR TO
BRYAN MANUFACTURING COMPANY, OF RACINE, WISCONSIN, A COR-
PORATION OF WISCONSIN.

ANTICREEPING DEVICE FOR RAILS.

No. 839,280.

Specification of Letters Patent.

Patented Dec. 25, 1906.

Application filed May 10, 1906. Serial No. 316,067.

To all whom it may concern:

Be it known that I, JENS JORGENSEN OVE FISCHER, residing in Racine, in the county of Racine and State of Wisconsin, have invented new and useful Improvements in Anticreeping Devices for Rails, of which the following is a description, reference being had to the accompanying drawings, which are a part of this specification.

10 My invention has relation to improvements in anticreeping devices for rails.

The primary object of the invention is to improve the construction covered in my issued United States Letters Patent No. 808,648, dated January 2, 1906, whereby the construction referred to is readily adapted for rails of varying widths of base.

With the above primary object and other incidental objects in view the invention consists of the devices and parts or their equivalents, as hereinafter set forth.

In the accompanying drawings, Figure 1 is a transverse section of a railway-rail equipped with my improvements, the tie being shown by dotted lines. Fig. 2 is a side elevation of Fig. 1. Fig. 3 is a plan view of the device removed from the rail. Fig. 4 is a detail view of one of the gripping devices, and Fig. 5 is a cross-section on the line 5 5 of Fig. 1.

30 Referring to the drawings, the numeral 6 indicates the rail, and 7 one of the supporting cross-ties.

The gripping device for one side of the rail-base (indicated by the letter A) is substantially similar to the corresponding gripping member shown and described in my issued patent hereinbefore referred to and consists of two lower jaws 8, the upper faces thereof when the device is adjusted to the base of the 40 rail adapted to underlie said rail-base, and an upper jaw 9, the under face thereof adapted to overlie the rail-base when the device is adjusted to the rail.

In each of the lower jaws 8 is set a gripping-bar 10, preferably of chilled iron or hardened steel. Each of these bars has one edge thereof projecting slightly above the face of the jaw, and in like manner there is set in the upper jaw 9 a gripping-bar 11, also preferably 50 of chilled iron or hardened steel and which has one edge projecting below the face of the jaw. The gripping member A is preferably a casting of malleable metal having recesses 12

cast therein to admit the gripping-bars 10 and 11, and which bars are preferably angular in cross-section to prevent their rotating in the said recesses. A lip 13 is left at the outer end of each recess. These lips in the original casting project outwardly, but are subsequently hammered down over the ends 60 of the gripping-bars, as shown most clearly in Fig. 4, to prevent the bars from working out of their sockets.

The gripping member A is provided with two side depending walls 14 and an outer 65 depending wall 15, one of said side walls being set to abut against the side of the tie 7 and the outer wall 15 provided through its upper portion with an opening 16.

The other gripping member B, which is 70 employed in connection with the gripping member A, consists of a bar having a hook 17 at one end, which engages over the side edge of the base of the rail opposite to the edge which is engaged by the gripping member A. 75 The bar B extends beneath the base of the rail, and its unhooked end passes through the opening 16 of the wall 15 of member A.

The features of my invention which constitute an improvement upon the construction 80 covered in my Letters Patent No. 808,648, hereinbefore referred to, will now be described. The end of the member B which projects beyond the opening 16 is provided with an elongated slot 18, the inner faces of 85 the walls of this slot being provided with a series of vertical recesses 19, each recess at one side being opposite to a recess at the opposite side. A key 20 is provided, and this key is formed on opposite sides and longitudinally thereof with ribs 21. The key is adapted to be passed into the elongated slot 18 by the engagement of the ribs 21 with any two of the opposite recesses 19, the side walls of the recesses and the outer faces of the ribs 95 being preferably beveled, so that a wedging engagement or locking of the key is provided when the key is brought into engagement as described and driven downwardly, and the key is thereby prevented from dropping 100 through the seat. The outer wall 15 and the web 22 extending therefrom, as well as the inner edge of the key, are also beveled, as most clearly shown in Fig. 1, so that when the key is driven downwardly the oppositely- 105 disposed gripping members A and B are

drawn toward each other and into close engagement with the opposite edges of the rail-base. It is advisable also that the hook 17 be provided with a gripping-bar adapted to bite into the side edge of the base of the rail to which said hook is adjusted, and thereby assist the gripping-bars 10 and 11 in preventing longitudinal movement of the device. To this end I provide the inner face of the back of the hook with a vertically-disposed gripping-bar 23, one edge of which projects beyond the face of said back of the hook and is adapted to bite against the side edge of the rail-base. This gripping-bar may be secured to the hook in any desirable manner; but I prefer to provide through the hook a square opening 24, in which the gripping-bar is disposed. At the upper end of the opening is left a lip 25, which originally projects upwardly from the hook, but which after the insertion of the bar into the square opening is adapted to be bent downwardly over the upper end of the opening, as shown most clearly in Fig. 3, in order to retain the bar 23 in place.

From Figs. 1 and 2 of the drawings the manner of using my invention will be readily understood. After the member B is properly adjusted with its hooked end in engagement with the edge of the rail-base the member A is adjusted onto the opposite end of the stem of the hook and the jaws of this member made to engage and grip the opposite faces of the rail-base. The key 20 is then inserted in place, the lips 21 thereof being made to engage the recesses 19 which are closest to the outer side 15 of the member A. If the device is to be adjusted to a rail having a base of a different width from the rail-base illustrated 40 in the drawings, the key 20 is of course adjusted accordingly. It will therefore be evident that notwithstanding variations of the width of rail-bases my improved construction is adapted to be applied thereto, and 45 when the key is inserted and driven downwardly the two members A and B, by reason of the beveled inner side of the key engaging the beveled outer side of the member A, are drawn toward each other and made to firmly 50 grip the opposite longitudinal edges of the rail-base.

What I claim as my invention is—

1. An anticreeping device for rails comprising a pair of jaws, means constructed to adjust and clamp the jaws to a rail, and other means for moving the jaws closer together after they have been clamped in their adjusted position.

2. An anticreeping device for rails comprising a pair of jaws adjustable toward and away from each other to engage rail-bases of varying widths, means constructed to adjust and clamp the jaws to a rail and a wedging means adapted, when the jaws are engaging 65 and clamped to the rail-base, to act on one of

the jaws and thereby hold said jaw in adjusted position and effect a clamping engagement of the jaws with the opposite sides of the rail-base at any of the adjusted positions of the jaws apart.

3. An anticreeping device for rails, comprising a bar having an engaging member at one end adapted to engage the edge of a rail-base, a gripping device adjustable longitudinally on the opposite end of the bar and adapted to grip the opposite edge of the rail-base, the said bar having an elongated slot extending longitudinally thereof, and means engaging the slot and operating on the gripping device, to hold said gripping device in its adjusted and clamping position, and other means for drawing said gripping device and the engaging member of the bar into clamping engagement with the opposite sides of the rail-base, after having been initially clamped in adjusted position.

4. An anticreeping device for rails, comprising a bar having an engaging member at one end adapted to engage the edge of a rail-base, a gripping member adjustable longitudinally on the opposite end of the bar, means constructed to adjust and clamp the jaws to a rail and other means, after the gripping member and the engaging member have been initially clamped in adjusted position, for drawing said engaging member and the gripping device toward each other and into further clamping engagement with the opposite side edges of the rail-base, and for retaining said parts in this clamping engagement.

5. An anticreeping device for rails, comprising a bar having an engaging member at one end adapted to engage the edge of a rail-base, and having its opposite end provided longitudinally with an elongated slot, the bordering side walls of said slot formed with a plurality of sets of recesses, a gripping device adjustable longitudinally on the slotted end of the bar and adapted to engage the opposite edge of the rail-base, and a key adapted to engage any two recesses constituting one of the sets.

6. An anticreeping device for rails, comprising a bar having an engaging member at one end adapted to engage the edge of a rail-base, and having its opposite end provided longitudinally with an elongated slot, the bordering side walls of said slot formed with a plurality of sets of recesses, and a key provided on its side edges with longitudinal ribs, said key adapted to be passed through the elongated slot, and the ribs thereof to engage any two recesses constituting one of the sets.

7. An anticreeping device for rails, comprising a bar having an engaging member at one end adapted to engage the edge of a rail-base, and having its opposite end provided longitudinally with an elongated slot, the bordering side wall of said slot formed with a

plurality of sets of recesses, the outer walls of said recesses being beveled, a gripping device adjustable longitudinally on the slotted end of the bar and adapted to engage the opposite edge of the rail-base, and a key provided on its side edges and longitudinally thereof with beveled ribs, said key adapted to be passed through the elongated slot, and the beveled ribs thereof to engage the beveled walls of any two of the recesses constituting one of the sets.

8. An anticreeping device for rails, comprising a bar having an engaging member at one end adapted to engage the edge of a rail-base, and having its opposite end provided longitudinally with an elongated slot, the bordering side walls of said slot formed with a plurality of sets of recesses, a gripping device adjustable on the slotted end of the bar and adapted to engage the opposite edge of the rail-base, the said gripping device provided with a beveled surface, and a key adapted to be passed through the elongated slot and to engage any two of the recesses constituting one of the sets, the inner side of said key provided with a beveled surface adapted to engage the beveled surface of the gripping device.

9. An anticreeping device for rails, comprising a bar having an engaging member at one end adapted to engage the edge of a rail-base, and having its opposite end provided

longitudinally with an elongated slot, the bordering side walls of said slot formed with a plurality of sets of recesses, the outer walls 35 of said recesses being beveled, a gripping device adjustable on the slotted end of the bar and adapted to engage the opposite edge of the rail-base, the said gripping device provided with a beveled surface, and a key having its 40 side edges provided longitudinally with beveled ribs, and its inner side provided longitudinally with a beveled surface, the said key adapted to be passed through the elongated slot, and the beveled ribs thereof to engage 45 the beveled walls of any two of the recesses constituting one of the sets, and the beveled surface on the inner side of the key adapted to engage the beveled surface of the gripping device. 50

10. An anticreeping device for rails, comprising a hook adapted to engage over the edge of a rail-base, a metal insert or biting tooth arranged vertically of the hook member and adapted to bite against the edge of 55 the rail-base, and a gripping member complementary to the hook, and adapted to grip the opposite edge of the rail-base.

In testimony whereof I affix my signature in presence of two witnesses.
